AUTOMATIC WINDOW STOP

George S. Gunard, 61 Pine Hill Ave., Glenbrook, Conn.
Filed Jan. 22, 1962, Ser. No. 167,574
4 Claims. (Cl. 292—75)

This invention relates to fasteners and more particularly to that type of fastener more commonly known as a window stop by reason of its use to securely hold a window or the like in any desired position.

Hardly a person alive has at one time or other not openly expressed a desire for a reliable window stop that will automatically hold the window in any desired position. While devices are admittedly on the market with claims of automatically holding windows open as one may desire, few, if any live up to the claims made for them.

It is, therefore, an object of this invention to provide a window stop of the automatic type that will at all times effectively hold the window in any desired position.

Another object of this invention is to provide an automatic window stop of the character described that will not jam by reason of its foolproof construction.

Another object of this invention is to provide an automatic window stop of the character described that can readily be adapted to any size and type of window.

Another object of this invention is to provide an automatic window stop that will not break the glass by reason of undue pressure on the sash.

Another object of this invention is to provide an automatic window stop having a minimum number of parts consistent with good design practice.

Another object of this invention is to provide an automatic window stop that can be manufactured and sold at a price well within the reach of everyone who desires a device of this type.

Another object of this invention is to provide an automatic window stop that will not scar any part of its frame no matter how constant the use.

Another object of this invention is to provide an automatic window stop that will eliminate the use of sash weights and cords.

Another object of this invention is to provide an automatic window stop that can, if necessary, be adjusted for maximum performance after it has been installed on the window.

Still another object of this invention is to provide an automatic window stop that can readily be installed by anyone no matter how limited their experience may be or how few tools they may have.

Other and further objects and advantages of this novel automatic window stop will be hereinafter described, and the novel features thereof defined in the appended claims.

Referring to the drawings:

FIGURE 1 is a pictorial view of the basic form of this invention installed on a typical sliding type of window.

FIGURE 2 is a pictorial view of an optional form of this invention installed on a window frame ready for use.

FIGURE 3 is a pictorial view of this invention in its basic form ready for installing on a window.

FIGURE 4 is a pictorial view of one detail of this invention rotated ninety degrees.

FIGURE 5 is an end view of the basic form of this invention.

FIGURE 6 is a sectional view taken substantially along line 6—6 of FIGURE 3 as viewed in the direction indicated by the arrows.

FIGURE 7 is a front exploded view of the form of this invention shown in FIG. 2.

2

Similar reference characters refer to similar parts throughout the several views of the drawings.

Having reference now to the drawings in detail, and in particular to FIGURES 3, 5 and 6, it will be seen that this invention consists of a U-shaped frame 12 having a pair of spaced openings 13 therein and a second pair of spaced openings 14 therein and at right angle to the first stated pair of openings which pass from top to bottom of the said frame while the second noted pairs of openings pass from side to side in the same said frame. The purpose of the openings 13 and 14 is to provide means for securing the frame to a window sash or frame as will be later on described in this specification.

A yoke 15 also U-shaped in plan form and having a stem 16 at the longitudinal center of the back is located within the said U-shaped frame 12 with the stem 16, on which has been placed a coil spring 17, projecting through an opening in the back of the said frame as clearly shown in FIGURES 5 and 6 of the appended drawings.

Returning again to the aforesaid frame 12, it will best be seen on examination of FIGURE 6 of the appended drawings that the frame is also provided with a pair of openings in the sides 18 of the said frame 12 are for the reception of alignment balls 19 which rest half in the openings and half on the yoke 15 when this novel automatic window stop is assembled. The openings in the sides 18 are diametrically opposite one another in order to insure a more stable structure. A coil spring 20 is also placed in each opening and on top of each alignment ball 19 which is held in place by the said coiled spring which in turn is prevented from springing out of the opening by a headless set screw 21 which by adjusting the pressure on each one of coiled springs 20 provides a means of alignment control of the said yoke 15 in which latter is rotatably mounted resilient cylinder means 22 having a plurality of concaved grooves 23 in circumferentially spaced relation and parallel to each other around its entire periphery as best shown in FIGURE 3 of the appended drawings where it is also seen that a groove 24 is formed completely around the circumference of the said cylinder means and in the longitudinal center of the same. This groove 24 has a depth nearly equal to the radius of the said cylinder means, forming a pair of rollers which are held in place in the aforesaid yoke 15 by means of a bolt 25 or its equivalent. The pair of rollers of course must be so mounted as to permit free turning within the said yoke.

The basic form of this novel invention of an automatic window stop has now been described with the exception of the placement of a locking pin 26 through an opening in the outer end of the stem 16 after the said yoke 15 and coil spring 17 have been placed within the frame 12 with the said stem 16 projecting through the already mentioned opening in the frame and with the spring 17 between the yoke 15 and the frame 12. The locking pin 26 of course holds the yoke in the frame which is now mounted on the top of a window "W" (FIG. 1) by means of screws 27 passing downward through the pair of openings 13 in the aforesaid frame 12 of this invention.

In the optional form of this automatic window stop the entire basic form of this invention is secured to the end of a pair of supporting members 28 that are rectangular in every plan form and which are each provided with a drilled recess for the reception of screws 29 as clearly shown in FIGURES 2 and 7. The said screws 29, of course, slidably pass through both the openings 14 in the frame 12 on through openings in members 28 into the window jamb 30.

While only two forms of this invention of a window stop are shown in the appended drawings, there is truth-

fully speaking no limitations in the number of optional forms this invention can be made up into merely by changing the method of mounting the aforementioned resilient cylinder means 22 on a window sill or frame.

As many embodiments may be made of this inventive concept, and as many modifications may be made in the embodiment hereinbefore shown and described, it will be understood that all matter herein is to be interpreted merely as illustrative, and not in a limiting sense.

What I now claim as my invention and desire to secure by Letters Patent is:

1. A window stop comprising, a frame having a back, a top, and a bottom so that the frame is substantially U-shaped when viewed from either end, a yoke having a back and ends so that the yoke is substantially U-shaped when viewed from the top or bottom, the yoke fitting into the frame with their backs substantially parallel and with the ends of the yoke extending forward, a resilient cylinder having an axis extending substantially from one end of the yoke to the other, means rotatably securing the cylinder to the ends of the yoke with a portion of the cylinder extending beyond the ends of the yoke, the back of the frame having a central opening, a stem secured to the back of the yoke and extending back through said opening, a compression spring encompassing the stem between the inside of the frame and the back of the yoke, spring biased antifriction means between the top and bottom of said frame and the back of said yoke, structure secured to the end of the stem for keeping the stem from passing out of said opening, and openings extending through the back of the frame lengthwise thereof for passage of screws for securing the window stop to the window frame.

2. A window stop comprising, a frame having a back, a top and a bottom so that the frame is substantially U-shaped when viewed from either end, a yoke having a back which is longer than the back of the frame, and ends so that the yoke is substantially U-shaped when viewed from the top or bottom, the yoke fitting into the frame with their backs substantially parallel and with the ends of the yoke extending forward, a resilient cylinder having an axis extending substantially from one end of the yoke to the other, means rotatably securing the cylinder to the ends of the yoke with a portion of the cylinder extending beyond the ends of the yoke, the back of the frame having a central opening, a stem secured to the back of the yoke and extending back through said opening, a compression spring encompassing the stem between the inside of the frame and the back of the yoke, spring biased antifriction means between the top and bottom of said frame and the back of said yoke, structure secured to the end of the stem for keeping the stem from passing out of said opening, openings extending through the back of the frame lengthwise thereof, and blocks having 55 openings aligned with the openings in the back of the frame, the blocks spacing the frame from the side of

the window when the frame is secured to the side of a window, by fasteners extending through said openings in the back of the frame and in the blocks.

3. In a window stop for holding window sash at any desired elevation comprising in combination, a base adapted to be fastened to a supporting structure; a member having arm means extending in one direction and a stem extending in an opposite direction, said stem being adapted to pass through a hole in said base and to reciprocate therein; spring-pressed ball means in said base adapted to cooperate with said member for providing free reciprocable movement of said member; a spring between said base and member, normally urging said member away from said base; means for limiting the extent of movement of said member away from said base; and roller means journaled on said arm means, whereby when said base is attached to a sash such that said roller means is in contact with a surface that is parallel with the path of sash movement, and with the spring between said base and member partly compressed, said sash is forced into frictional contact with its track to thereby hold said sash at any desired elevation without inhibiting the raising and lowering of said sash.

4. In a window stop for holding window sash at any desired elevation comprising in combination, a base member adapted to be fastened to a supporting structure; a yoke having parallel spaced arms extending in one direction and a stem extending in an opposite direction, said stem being adapted to pass through a hole in said base member and to reciprocate therein; spring-pressed ball means in each arm adapted to cooperate with said yoke for providing free reciprocable movement of said yoke; a spring between said base member and yoke, normally urging said yoke away from said base member; means for limiting the extent of movement of said yoke away from said base member; and roller means journaled between the arms of said yoke, whereby when said base member is attached to a sash such that said roller means is in contact with a surface that is parallel with the path of sash movement, and with the spring between said base member and yoke partly compressed, said sash is forced into frictional contact with its track to thereby hold said sash at any desired elevation without inhibiting the raising and lowering of said sash.

CERTIFICATE OF CORRECTION

Patent No. 3,141,691

July 21, 1964

George S. Gunard

It is hereby certified that error appears in the above numbered patent requiring correction and that the said Letters Patent should read as corrected below.

Column 1, line 27, for "adapated" read -- adapted --; line 64, for "degress" read -- degrees --; line 68, for "asectional" read -- a sectional --; column 2, line 4, for "been" read -- be seen --; line 12, for "for" read -- of --; line 22, for "been" read -- be --; line 34, after "of" insert -- the --; line 61, for "inventoin" read -- invention --; column 3, line 28, for "antifraction" read -- antifriction --; column 4, line 52, in the references cited, for "1,697,244" read -- 1,679,244 --.

Signed and sealed this 24th day of November 1964.
